Primary Examiner — Derrick Holland(74) *Attorney, Agent, or Firm* — Seth Natter; Natter & Natter(57) **CLAIM**

The ornamental design for an outdoor electrical device cover, as shown and described.

DESCRIPTION

FIG. 1 is an isometric view of an outdoor electrical device cover showing my new design;

FIG. 2 is a front elevational view thereof;

FIG. 3 is a top plan view thereof;

FIG. 4 is a bottom plan view thereof;

FIG. 5 is a right side elevational view thereof;

FIG. 6 is a left side elevational view thereof

FIG. 7 is a rear elevational view thereof; and,

FIG. 8 is a bottom and side isometric view thereof.

The broken lines shown represent unclaimed subject matter and form no part of the claimed design.
